UNITED STATES PATENT OFFICE.

LE ROY E. JOLLS, OF DETROIT, MICHIGAN, ASSIGNOR TO PACKARD MOTOR CAR COMPANY, OF DETROIT, MICHIGAN, A CORPORATION OF MICHIGAN.

METHOD OF GRINDING.

Original application filed June 20, 1918, Serial No. 241,041. Divided and this application filed October 15, 1920. Serial No. 417,227.

To all whom it may concern:

Be it known that I, LE ROY E. JOLLS, a citizen of the United States, and residing at Detroit, Wayne Co., Michigan, have invented 5 certain new and useful Improvements in Methods of Grinding, of which the following is a specification.

This application which is a division of application 241,041, filed June 20, 1918, relates to a method for grinding one or both 10 of the peripheral surfaces of a ring so that they will be truly concentric with the axis of the ring and the axis truly perpendicular to the side faces of the ring. To this end 15 the invention consists in placing the ring with a side thereof against a rotatable member having a flat surface perpendicular to the axis of rotation, centering the ring on said flat surface, holding the ring in its centered position, rotating the member and 20 machining one of the peripheral surfaces of the ring by a tool movable perpendicularly to the said flat surface.

The objects and novel features of the invention will be apparent from the description taken in connection with the drawings, in which:

Figure 1 is a side elevation of a metal working machine for practicing the present invention certain parts being shown in section, the tool holder being omitted;

Figure 2 is an end elevation of the magnetic chuck and casing surrounding the same; and

Figure 3 is a plan view of a part of the machine.

Referring to the drawings which illustrate the at present preferred form for carrying out the invention the reference numeral 10 indicates a support which carries a bracket 11 having the upwardly projecting spaced bearing arms 12. The tube 13 is rotatively mounted in the bearing arms and projects from the outer side of either of said bearing arms. A driving pulley 14 is arranged between the bearing arms and mounted on the tube 13 being connected to rotate therewith in any suitable manner. The right hand end of the tube 13 as shown 45 in Figure 1 is threaded and carries a magnetic chuck, which comprises a disk 15 having a hub 14 screwed on said threaded end, the outer periphery of the disk having the axially extending flange 16 which with the

hub 14 forms an annular recess 17. Con- 55 ductor rings 18 and 19 are arranged as shown and insulated from each other by the insulating material 20 filling the recess 17. Spring contact brushes 21 and 22 connected with a source of electricity are in 60 electric contact with the rings 18 and 19 respectively, these brushes being supported on a block 23. As this construction of brushes is well known it is not necessary to describe or illustrate the same in detail. 65

A cup shaped member 24 has a peripheral flange or lip 25 which is secured against the annular seat 26 in the face of the disk 15 by means of the cap screws 27. A circularly arranged series of coils 28 are located 70 within the member 24, four coils being shown in the present embodiment of the invention. Each coil has a core 29 which as shown in Figure 1 is L-shaped in cross section, the base 30 of the L being set in a recess 31 75 in the base or face of the cup shaped member 24 so that it is flush with the said face. At the tip of the base the L-shaped core has a lip 32 which together with a projecting portion on the member 24, form a boss 33, 80 the front or end face of this boss being finished so that it is in a plane truly perpendicular to the axis of rotation of the chuck. The base of the member 24 is formed with the bore 34 and the counterbore 35, a 85 sleeve 36 being interposed between the end of the sleeve 13 and the base of the member 24 and having one end seated in said counterbore. An annular disk 37 having contact with the member 24 and the sleeve 36 90 is secured to the end of the cores 29 in magnetic contact therewith by means such as the cap screws 38. Thus the coils 28 and cores 29 are securely held against displacement and an arrangement of parts is provided which forms a closed metallic magnetic circuit with the cores 29. A sheet metal casing 54 is arranged around the portion of the chuck between the bearing 12 and the flange 25. 95

As previously stated one of the principal objects of the present invention is to finish the bore and periphery of a ring or roller such as shown in dotted lines at 39 so that the axis thereof will be truly perpendicular to a side face of the roller. As the face of the boss 33 which may be termed the face of the chuck is truly perpendicular to the axis 100 105

of rotation, a roller positioned as shown in Figure 1, will of course have its side face which is in contact with the face of the chuck also truly perpendicular to the axis of 5 rotation of the chuck. In order to arrange the roller 39 so that its axis will be coaxial with the axis of rotation of the chuck, a centering pin or spindle 40 is slidingly mounted in the sleeve 36 so that it may be 10 projected from the face of the chuck to engage the bore of a roller 39, thereby centering the roller with respect to the axis of the chuck. In order to aid in properly positioning the roller the end of the centering 15 pin 40 is slightly tapered as shown at 40°. After the roller has been centered by the projecting pin, the latter is retracted to the position shown in Figure 1. For the purpose of operating the centering pin, which 20 is hollow, that is in the form of a tube, it is connected to a tube 41 by means such as the nipple 42, the tube 41 extending through the tube 13 and projecting from the left end thereof, as shown in Figure 1. As the outer 25 end of the centering pin is subjected to more or less wear, and this end must be of absolutely correct size, the pin is made separable from the tube 41 so that it may be replaced when necessary. The left end of tube 13 is 30 threaded and has a flanged sleeve 43 screwed thereon which carries a tubular extension 44, the tube 41 being slidingly mounted in this extension 44. The tube 41 and centering pin 40 thus form a continuous tubular member, having supporting bearings at its ends in the extension 44 and sleeve 36. In order 35 to limit the sliding movement of the centering pin 40, the tube 41 is formed with the slot 45 and the sleeve 43 has a set screw 40 46 extending through both sleeve 43 and extension 44, the reduced end of the set screw 46 projecting into said slot. The length of sleeve 44 is such that it covers the slot 45. At its left hand end the rotatable tube 41 is 45 connected by means of a coupling 46 of any desired construction to the non-rotatable nipple or pipe 47 having communication with a source of compressed air.

According to the method of this invention 50 a ring or roller such as 39 is placed against the face of the magnetic chuck being centered thereon by means of the projected centering pin 40. Then the chuck is energized which of course holds the roller in its centered 55 position against the face thereof, and immediately thereafter the centering pin 40 is retracted by the operator grasping the coupling 46 and moving it toward the left as viewed in Figure 1. The grinding tool 60 48 mounted on a turret or rotative support 49 is moved up into operative position by sliding said turret on its ways 50, the path of the tool being truly parallel to the axis of rotation of the chuck. The tool 48 is for 65 the purpose of finishing the bore of the

roller 39. In order to finish the periphery of the roller, a tool 51 is provided and mounted on the turret 49 in such position that when the turret is turned substantially 70 90° the tool will be brought to a position where it may operate on the periphery of the roller. In order to securely hold the turret in either of the two positions for the operation of one or the other of the tools 48 and 51 a catch or lock 52 of any desired construction may be provided. It will be apparent that the boss 33, which is of smaller diameter than the roller to be finished, is provided so that the roller will be held in a position such that the tool 51 may move 75 80 across its periphery. In a machine where it is only desired to finish the bore of the rollers, of course the boss would not be necessary.

In order to keep the bore 34 of the chuck 85 free from dust, air under pressure is conducted to the bore through the tube 41 and centering pin 40. The dust may be blown out of the bore directly or through the radial ducts 53 formed in the base of the member 24 leading from the bore to the periphery of the chuck, the inner ends of these ducts opening into the bore in advance of the retracted position of the centering pin.

It is apparent from the foregoing description 95 that the present invention provides an exceedingly simple and accurate method of finishing the peripheries of a hollow roller by centering one face of the roller adjacent the face of a chuck which is truly perpendicular to its axis, the centering operation being accomplished by retractable means engaging one of the surfaces to be finished.

Although a specific machine has been described for carrying out the method it is 105 to be understood that the invention is not limited to the exact construction but includes any structure capable of carrying out the method.

Having thus described the invention what 110 I claim as new and desire to secure by Letters Patent is:

1. The method of finishing the outer cylindrical surface of a roller and its bore with 115 said surfaces concentric and perpendicular to a side of the roller consisting in placing the roller with a side against the flat face of a rotatably mounted electromagnet, said face being of smaller diameter than the roller, centering the roller by means engaging 120 one of the surfaces to be finished, energizing the magnet, removing the centering means, rotating the electromagnet, and machining the surfaces by tools movable perpendicularly to said flat faces.

2. The method of finishing the bore of a roller consisting in centering the roller on a pin engaging the bore thereof, supporting the roller in its centered position, withdrawing the pin, and grinding said bore.

3. The method of finishing the bore of a roller with its axis perpendicular to a face thereof consisting in, centering the roller against a flat surface by means cooperating with the bore, magnetically holding the roller in its centered position, withdrawing the centering means, rotating the holding device and machining the bore by a tool movable perpendicularly to said flat surface.
- 5 4. The method of finishing the bore of a roller with its axis perpendicular to a face thereof consisting in, centering the roller against a flat surface by means cooperating with the bore, holding the roller in its cen-
- tered position, withdrawing the centering means, rotating the holding device and machining the bore by a tool movable parallel to the axis of said holding device.
- 10 5. The method of finishing the bore of a roller consisting in centering the roller in a rotatable holding device by means cooperating with the bore, holding the roller in its centered position, removing the centering means, rotating the holding device and machining the bore by a tool movable parallel to the axis of said holding device.

In testimony whereof I affix my signature.

LE ROY E. JOLLS.
